US00D823874S

(12) **United States Design Patent** (10) Patent No.: **US D823,874 S**
Yuguchi et al. (45) Date of Patent: **** Jul. 24, 2018**

(54) **DISPLAY SCREEN WITH GRAPHICAL USER INTERFACE**

(71) Applicant: **MITSUBISHI ELECTRIC CORPORATION**, Tokyo (JP)

(72) Inventors: **Takashi Yuguchi**, Tokyo (JP); **Kazuhiro Hayashi**, Tokyo (JP)

(73) Assignee: **Mitsubishi Electric Corporation**, Tokyo (JP)

(**) Term: **15 Years**

(21) Appl. No.: **29/601,717**

(22) Filed: **Apr. 25, 2017**

(30) **Foreign Application Priority Data**

Nov. 9, 2016 (JP) 2016-024404

(51) **LOC (11) Cl.** **14-04**

(52) **U.S. Cl.**

USPC **D14/486**

(58) **Field of Classification Search**

USPC D14/485-495
